CASSIUS C. SMILEY, OF GREENSBURG, INDIANA

MATCH BOX

Application filed December 12, 1928. Serial No. 325,487.

The present invention relates to improvements in match boxes and has reference more particularly to a device for dispensing only one match at a time.

One of the important objects of the present invention is to provide a match box of the above mentioned character which includes means for normally retaining the matches in the match holding compartment so that the same cannot accidentally be discharged from the box.

Still a further object is to provide a match box of the above mentioned character that will at all times be positive and efficient in its operation, the same being of such construction, as to adapt its use upon automobiles, cigar stands and the like within convenient reach.

A further and important object is to provide a match box of the above mentioned character which is simple in construction, inexpensive, strong and durable and further well adapted to the purposes for which it is designed.

Other objects and advantages will become apparent during the course of the following description.

In the accompanying drawing, forming a part of this specification, and in which like numerals indicate like parts throughout the same:

Figure 1 is a side elevation of a match box embodying my invention,

Figure 2 is a fragmentary perspective view of the upper portion of the casing showing the closure lid disengaged therefrom and the upper portion of the match box protruding above the open upper portion of the casing,

Figure 3 is a top plan view of the casing with the lid removed for more clearly disclosing the leaf spring arranged in the bottom of the casing,

Figure 4 is a sectional view taken approximately on the line 4-4 of Figure 1, and

Figure 5 is a detail perspective view of the leaf spring per se.

In the drawings, wherein for the purpose of illustration is shown the preferred embodiment of my invention, the numeral 1 designates a substantially rectangular shaped

metallic casing that is open at its top and as is more clearly shown in Figure 2, the upper portion of this casing is reduced for receiving flanged lids or cap 2 that has a sliding fit with the reduced portion 3 of the casing.

The top face of the removable lid or cap is primed with a striking surface 4. As is clearly illustrated in Figure 1, the front side of the casing is formed with an enlarged centrally located opening 5 that extends upwardly from the lower edge portion of the casing to the intermediate portion thereof.

This side of the casing is furthermore formed with a longitudinally extending slot 6 at the lower edge thereof and this slot extends from one side of the opening 5 to the adjacent end of the casing to form a restricted passage for the delivery of a single match in the manner to be presently described.

Adapted to be removably disposed within the casing 1 is the container 7 in which the matches are confined, the front side of the container being open. The container is placed within the casing 1 in such a manner as to dispose the heads of the notches remotely from the slot 6 and this is clearly shown in Figure 1. When the lid 2 is fitted over the reduced upper portion 3 of the casing 1, the container 7 is held within the casing.

Also forming a salient part of the present invention is the leaf spring 8 that is secured at one end within the bottom of the casing 1 and this leaf spring has a tendency to normally urge the package or container of matches 7 upwardly as shown very clearly in Figures 1 and 4.

The intermediate portion of the forward longitudinal side of the leaf spring is cut away as at 9 to coincide with the opening 5 and in Figure 5 of the drawing, there is shown in detail the construction of the leaf spring element per se.

Any appropriate means may be provided for attaching the match box to a support and the device is capable of being attached to the instrument board of an automobile, upon a cigar stand, where the same can be conveniently reached.

In use, the matches are held within the

casing against accidental discharge by reason of the leaf spring 8. However whenever a person desires to light a cigarette or cigar, the forefinger is placed in the opening 5 and 5 a downward pressure is exerted on the matches so as to move the free end of the leaf spring 8 downwardly against the bottom of the casing and this will result in the lowermost match being positioned in registration with the slot 6 whereupon the alined 10 match may be readily withdrawn from the case and the head of the match may be caused through the crossly striking surface, to ignite the same.

15 In this manner, only one match will be delivered during each operation of the match box and furthermore the opening 5 provides a means for enabling a person to readily ascertain when the match box must be refilled.

20 While I have shown the match box as being adapted to receive and hold snugly the original paste board box or container of a penny box of domestic box of matches, the device can equally be operated without a 25 container for the matches and loose matches may be placed in the casing.

While I have shown the match box as being adapted to receive a package or container of matches, the device can be equally operated without a container for the matches and loose matches may be placed in the casing.

30 A match box of the above mentioned character can be constructed at a very low cost 35 and the same will at all times be positive and efficient in carrying out the purposes for which it is designed. Also due to its simplicity of construction, the match box can be manufactured and sold at a very low 40 cost.

45 While I have shown the preferred embodiment of my invention it is to be understood that various changes in the size, shape and arrangement of parts may be resorted to without departing from the spirit of the invention and the scope of the appended claims.

Having thus described my invention, what I claim as new is:

50 1. A match box of the class described, a casing formed in one side with an opening in the intermediate portion thereof and which opening extends from the bottom of the casing to the intermediate portion thereof, said side of the casing being further formed with 55 a longitudinal slot that extends from one side of the opening to the adjacent end of the casing and being located at the bottom edge of said side to provide a restricted passage for the delivery of a single match, and 60 means within the casing for normally urging the matches upwardly and to maintain the lowermost match above the slot, said last mentioned means comprising a leaf spring secured at one end in the bottom of the casing 65 remotely of the slot.

2. A match box of the class described comprising an open top casing adapted to receive a supply of matches disposed in longitudinally stacked relation, a closure for the open top casing, the front side of the casing being formed with a central opening that extends upwardly from the lower edge to the intermediate portion thereof, said front side being formed with a longitudinally extending slot that extends from one side of the central opening to the adjacent end of the casing, the lower edge of the longitudinal slot being disposed adjacent the bottom of the casing to provide a restricted passage for the discharge of a single match, and a leaf spring 70 attached at one end to the bottom of the casing at a point remote of the slot, the free end portion of the leaf spring engaging the stack of matches for normally urging the same upwardly and to maintain the lowermost match of the stack above the slot.

75 In testimony whereof I affix my signature,
CASSIUS C. SMILEY.
